INTERNAL COMBUSTION ENGINE

Fritz Huber, Mannheim, Germany, assignor to
Heinrich Lanz A.-G., Mannheim, GermanyApplication November 29, 1939, Serial No. 306,645
In Germany November 16, 1934

6 Claims. (Cl. 123—33)

This invention relates to an internal combustion engine provided with an eddy chamber.

In eddy chamber engines having a vertical ignition or discharge duct it is known to arrange 5 the nozzle in the direction of the duct so that fuel is squirted into the cylinder when the engine is started. It is further known to have the discharge duct enter obliquely at the edge of the cylinder and to construct a portion of the eddy 10 chamber in the form of a removable separate member which is heated from the outside.

The invention differs from the known art in providing for a novel arrangement of the removable member, the nozzle and an electric heating 15 means in eddy chamber engines in which the nozzle and the discharge duct are disposed obliquely and nearly alike in such manner that during starting fuel is squirted approximately at the edge of the cylinder into the gap formed between the piston head and the cylinder cover. 20 The feature of the invention is that the removable or insertable member constituting the uncooled portion of the eddy chamber and being heatable from without extends from the nozzle 25 at least up to the discharge duct and that the electric heating means is positioned at the other side of the nozzle.

This arrangement involves the following advantages: The uncooled removable member may 30 be made relatively large with respect to the cooled portion of the eddy chamber, and it may be taken out without interfering with other connections to permit inspection of the eddy chamber, the discharge duct and of the piston head 35 from the outside. Furthermore, the construction of the cylinder cover is quite simple with respect to the casting and machining work involved, it avoids protruding parts and leaves sufficient space on the cylinder for the accommodation 40 of large valves, the eddy chamber, the removable member and the heating means being all contained within the cover.

The invention is illustrated by way of example 45 in the accompanying drawing, in which Figures 1 and 2 show two constructional embodiments of the invention.

In the constructions shown, 'a' represents the cylinder; 'a', the edge of the cylinder; 'b', the cylinder cover; 'c', the eddy chamber; 'd', the discharge duct; 'e', the nozzle; and 'f', an electric heating device. In both embodiments the axis 50 of the nozzle 'e' is arranged at an acute angle to the axis of the duct 'd' which tangentially enters the eddy chamber 'c' and extends at an acute angle to the axis of the cylinder 'a'. 55

In Fig. 1 the letter 'g' and in Fig. 2 the letter 'i' designate the removable or insertable member whose bottoms 'h' and 'k', respectively, form the withdrawable portion of the eddy chamber 'c'. The parts 'h' and 'k' are located directly and on one side 5 next to the nozzle 'e', and the heating device 'f' is disposed at the other side thereof. The central axes of the members 'g' and 'i' lie in planes running either at right angles (Fig. 1) or parallel (Fig. 2) to the cylinder axis. As shown in 10 Fig. 2, the axis of the removable member 'i' is positioned between the cylinder axis and the equidirected axis of the eddy chamber 'c'.

In the construction shown in Fig. 1 the member 'h' extends up to the discharge duct 'd'. 15

In Fig. 2 the removable member 'i' has been drawn down to the edge of the cylinder and in its lower portion takes up the discharge duct 'd'. To insure uniform temperature of the eddy 20 chamber 'c' in the latter construction a free space 'i' must remain between the member 'k' and the opposite wall and extend up to the combustion space of the cylinder.

I claim:

1. A cylinder head for an internal combustion 25 engine comprising, in combination, an eddy engine comprising, in combination, an eddy chamber, passage means tangentially connected with said eddy chamber and being inclined with respect to the head wall and to the axis of the engine cylinder a fuel nozzle means terminating 30 in said eddy chamber and having an axis inclined with respect to the cylinder axis generally in the same direction as is the axis of said passage means, a heating device terminating in said eddy chamber on one side of said nozzle means, 35 and a substantially hollow, uncooled removable member disposed on the other side of said nozzle means and having a curved surface portion forming a part of the interior wall of said eddy chamber extending from said nozzle to said 40 passage means.

2. A cylinder head for an internal combustion 45 engine comprising, in combination, an eddy chamber, passage means tangentially connected with said eddy chamber and being disposed at an acute angle with respect to the axis of the engine cylinder, a fuel nozzle means terminating in said eddy chamber and having an axis inclined with respect to the cylinder axis in substantially the same direction as is the axis of 50 said passage means, a heating device disposed laterally with respect to said nozzle means and terminating in said eddy chamber, and a substantially hollow, uncooled plug member removable directly from outside and disposed at the 55

- side of said nozzle means opposite the side where said heating device is located and having a curved surface portion forming a substantial portion of the interior wall of said eddy chamber, 5 said portion extending from said nozzle to said passage means.
3. A cylinder head for an internal combustion engine comprising, in combination, an eddy chamber, passage means tangentially connected 10 with said eddy chamber and being inclined with respect to the head wall and to the axis of the engine cylinder a fuel nozzle means terminating in said eddy chamber and having an axis inclined with respect to the cylinder axis generally 15 in the same direction as is the axis of said passage means, a heating device disposed laterally with respect to said nozzle means and terminating in said eddy chamber, and a substantially hollow, uncooled removable member having a 20 curved surface portion forming a substantial portion of the interior wall of said eddy chamber, said portion extending from said nozzle to said passage means and continuing tangentially into a wall portion of said passage means.
- 25 4. A cylinder head for an internal combustion engine comprising, in combination, an eddy chamber, passage means tangentially connected with said eddy chamber and being inclined with respect to the head wall and to the axis of the 30 engine cylinder, a fuel nozzle means terminating in said eddy chamber and having an axis inclined with respect to the cylinder axis generally in the same direction as is the axis of said passage means, a heating device disposed laterally 35 with respect to said nozzle means and terminating in said eddy chamber, and a substantially hollow, uncooled removable pluglike member having a curved surface portion forming a part of the interior wall of said eddy chamber extending from said nozzle to said passage means and having a wall portion tangentially continuing into a wall portion of said passage means, the 40 axis of said pluglike member being disposed sub-

stantially at a right angle with respect to the axis of the engine cylinder.

5. A cylinder head for an internal combustion engine comprising, in combination, an eddy chamber passage means tangentially connected 5 with said eddy chamber and being inclined with respect to the head wall and to the axis of the engine cylinder, a fuel nozzle means terminating in said eddy chamber and having an axis inclined with respect to the cylinder axis in substantially 10 the same direction as is the axis of said passage means, a heating device disposed laterally with respect to said nozzle means and terminating in said eddy chamber, and a substantially hollow, uncooled removable pluglike member having a 15 curved surface portion forming a part of the interior wall of said eddy chamber extending from said nozzle to said passage means, said pluglike member being disposed between the axis of the engine cylinder and said nozzle means and removable directly from outside and including said passage means.

6. A cylinder head for an internal combustion engine comprising, in combination, an eddy chamber, passage means tangentially connected 25 with said eddy chamber and being inclined with respect to the head wall and to the axis of the engine cylinder, a fuel nozzle means terminating in said eddy chamber and having an axis inclined with respect to the cylinder axis in substantially 30 the same direction as is the axis of said passage means, a heating device disposed laterally with respect to said nozzle means and terminating in said eddy chamber, and a substantially hollow, uncooled pluglike member removable 35 directly from outside and having a curved surface portion forming a part of the interior wall of said eddy chamber extending from said nozzle to said channel means, said pluglike member including said passage means, and having a 40 cavity extending around said curved surface portion and adjacent to said passage means and the engine cylinder.
